(57) **CLAIM**

The ornamental design for an airway device, as shown and described.

DESCRIPTION

FIG. 1 is a front view of an airway device showing the new design.

FIG. 2 is a rear view of the airway device shown in FIG. 1. FIG. 3 is a top view of the airway device shown in FIG. 1. FIG. 4 is a bottom view of the airway device shown in FIG. 1.

FIG. 5 is a left side view of the airway device shown in FIG. 1.

FIG. 6 is a right side view of the airway device shown in FIG. 1.

FIG. 7 is a bottom, right perspective view of the airway device shown in FIG. 1.

FIG. 8 is a top, left perspective view of the airway device shown in FIG. 1.

FIG. 9 is a bottom, rear perspective view of the airway device shown in FIG. 1; and,

FIG. 10 is a top, front perspective view of the airway device shown in FIG. 1.

The broken lines in the drawings illustrate portions of the airway device that form no part of the claimed design.
